US00D802767S

(12) **United States Design Patent** (10) **Patent No.:** **US D802,767 S**
(45) **Date of Patent:** **** Nov. 14, 2017**

(54) **ROOT PART FOR A DENTAL IMPLANT**

(71) Applicant: **Silvio Franco Emanuelli**, Sanremo (IT)

(72) Inventor: **Silvio Franco Emanuelli**, Sanremo (IT)

(**) Term: **15 Years**

(21) Appl. No.: **29/595,388**

(22) Filed: **Feb. 28, 2017**

Related U.S. Application Data

(63) Continuation of application No. 29/553,912, filed on Feb. 5, 2016, now Pat. No. Des. 783,826.

(51) **LOC (10) Cl.** **24-02**

(52) **U.S. Cl.**

USPC **D24/156**

(57) **CLAIM**

The ornamental design for a root part for a dental implant, as shown and described.

DESCRIPTION

This application is also related to U.S. patent application Ser. No. 29/553,916, filed on Feb. 5, 2016 and entitled “Post Part for a Dental Implant,” U.S. patent application Ser. No. 29/553,886, filed on Feb. 5, 2016 and entitled “Post Part for a Dental Implant,” U.S. patent application Ser. No. 29/553,904, filed on Feb. 5, 2016 and entitled “Post Part for a Dental Implant,” U.S. patent application Ser. No. 29/553,881, filed on Feb. 5, 2016 and entitled “Root Part for a Dental Implant,” and U.S. patent application Ser. No. 29/553,896, filed on Feb. 5, 2016 and entitled “Root Part for a Dental Implant.”

FIG. 1 is a perspective view of a root part for a dental implant showing my new design;

FIG. 2 is a side view thereof;

FIG. 3 is a side view thereof;

FIG. 4 is a side view thereof;

FIG. 5 is a side view thereof;

FIG. 6 is a top view thereof; and,

FIG. 7 is a bottom view thereof.

The broken line showing is included for the purpose of illustrating unclaimed subject matter and forms no part of the claimed design.

1 Claim, 4 Drawing Sheets
